UNITED STATES PATENT OFFICE.

SEVERT M. SEVERSON, OF ALBERT LEA, MINNESOTA.

STORM-WINDOW HOLDER.

Application filed March 6, 1923. Serial No. 623,131.

To all whom it may concern:

Be it known that I, SEVERT M. SEVERSON, a citizen of the United States, residing at Albert Lea, in the county of Freeborn, State of Minnesota, have invented a new and useful Storm-Window Holder; and I do hereby declare the following to be a full, clear, and exact description of the invention, such as will enable others skilled in the art to which it appertains to make and use the same.

The invention relates to storm window holders and has for its object to provide a device of this character comprising an outwardly movable arm formed from a plurality of pivotally connected members and disposed between the storm window and the lower sash and forming means whereby the storm window may be held either closed or in various open positions. The pivotally connecting members form means whereby said members may be disposed at a right angle to each other between the storm window and the lower sash, consequently allowing a large range of adjustability.

A further object is to provide a U-shaped bracket secured to the upper side of the window sill, said bracket being provided with a clamping jaw for clamping and holding the pivoted sections after they have been adjusted to the desired position. Also to provide the inner pivoted member with a right angled portion at its end, which right angled portion forms means for preventing the inner pivoted member from passing outwardly from engagement with the bracket and pivoted member.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a horizontal sectional view through a window frame and sash, showing the device disposed between the sash and storm window.

Figure 2 is a perspective view of the device.

Figure 3 is a detail sectional view through a portion of the U-shaped bracket.

Referring to the drawing, the numeral 1 designates a conventional form of window

frame, 2 the lower sash thereof and 3 the storm window. The storm window 3 is hingedly connected at 4 to the window frame 1 and is adapted to be moved outwardly in the direction of the arrow *a* to various positions, and held in said positions by the window holding device 5. The window holding device 5 is adapted to be adjusted in such a manner that the storm window 3 may be locked in closed position or at various open positions, for instance, for ventilating purposes. Secured to the upper side of the window sill 6 is a U-shaped bracket 7, which bracket is provided with a horizontally disposed portion 8, on which any of the pivoted sections 9, 10 or 11 of the storm window holding arm may be clamped and held by the hinged jaw 12, which is hingedly connected at 13 to the U-shaped member 7. Extending through the horizontally disposed portion 8 of the U-shaped bracket and the hinged jaw 12 is a bolt 14, which bolt is provided with a thumb screw 15, whereby the hinged jaw 12 may be forced into close and binding engagement with one of the sections 9, 10 or 11 for holding the storm window 3 in adjusted position. The section 9 is pivotally connected at 16 to a bracket 17 carried by the storm window and it will be seen that by pivotally connecting the sections 9, 10 and 11 that the sections disposed rearwardly of the bracket 7 may be positioned between the storm window and the lower sash 2 where they will not interfere with the operation of the lower sash 2 as clearly shown in Figure 1. It will also be seen that when the sections 10 or 11 are disposed in position to the inner side of the brackets 7, that said sections will engage the inner side of the bracket 7 in such a manner that they cannot be forced between the horizontally disposed portion 8 and the pivoted jaw 2, consequently preventing the storm window from being forced open. The end 18 of the pivoted member 11 is provided with a right angularly disposed portion 19, which portion prevents the section 11 from passing entirely through the clamping means, and consequently prevents the storm window from moving to extreme open position with the bar out of engagement with the clamping means. Interposed between the hinged jaw 12 and the horizontally disposed portion 8 is a coiled spring 20, which spring, when the thumb nut 15, is loosened forces

the hinged jaw 12 upwardly and holds the same in raised position during the storm window adjusting operation.

From the above it will be seen that a storm window holding and adjusting device is provided, which device is simple in construction, will positively hold the window in any position to which it may be moved and is constructed in such manner that it is entirely disposed between the storm window and an adjacent window sash, thereby not interfering with the operation of the window sash.

The invention having been set forth what is claimed as new and useful is:

The combination with a hinged storm window, said window being carried by a window frame, a sash slidably mounted in the window frame, of an adjusting and holding device for said storm window and entirely disposed between the storm window and the window sash, said adjusting and holding device comprising an arm pivotally

connected to the storm window, said arm being formed from a plurality of pivotally connected sections foldable into registration with each other, and a clamping device carried by the window sill between the sash and storm window and cooperating with all of said plurality of pivotally connected sections, said clamping member comprising a U-shaped bracket, said bracket having its transverse portion downwardly offset, thereby forming shoulders between which the pivoted sections of the arm extend, a clamping jaw carried by one of said shoulders and pivotally connected thereto, and a set screw extending through said jaw and the transverse portion of the bracket for securely clamping the arm between the jaw and bracket and the shoulders carried by the bracket.

In testimony whereof I have signed my name to this specification.

SEVERT M. SEVERSON.
